 N. J., a corporation of New Jersey

Application December 26, 1933, Serial No. 703,925

6 Claims. (Cl. 229—8)

This invention relates to an improvement in boxes, and more particularly to boxes having an irregular outline, and has for its object to provide a box of improved construction, composed 5 of sheet material such as cardboard, fibre, thin wood or the like. A box made in accordance with the invention possesses strength and sturdiness in excess of boxes constructed in the usual way from sheet card board. The invention also 10 contemplates making the boxes of regular and irregular outline by which they may be speedily, accurately and neatly made with a minimum of time and effort and without the use of expensive tools and dies.

15 More specifically, the invention contemplates a box composed of a number of apertured contiguous layers or laminae adhesively united to "build up" a merchandise-holding compartment of requisite shape and depth, the apertured 20 layers being closed on one face by an imperforate bottom sheet and either removably or permanently closed on the other face by a cover sheet. The method employed in making the box is such that the box may be made in numerous shapes, 25 sizes and styles according to the articles to be contained in it.

In the accompanying drawings, wherein several 30 embodiments of the invention are shown, Fig. 1 is a perspective view of a piece of sheet material showing the first step in blanking out one of the members which forms a lamina or layer of the body of the box; Fig. 2 is a perspective view of one of the box body layers after it has been fully 35 stamped out from the sheet shown in Fig. 1; Fig. 3 is a perspective view of a hinged box shown in open position; Fig. 4 is a sectional view on the line 4—4 of Fig. 3, looking in the direction of the arrows, the box being shown in a partly closed position; Fig. 5 is a sectional view on the 40 line 5—5 of Fig. 6, looking in the direction of the arrows; Fig. 6 is a plan view, with parts broken away, of a type of box provided with a sliding tray; Fig. 7 is a plan view of a box body intended 45 for the reception of a bottle or other irregularly shaped article; Fig. 8 is a sectional view on the line 8—8 of Fig. 7, looking in the direction of the arrows, a cover being shown partly in place on the box; and Fig. 9 is a perspective view of a 50 modified structure wherein the box compartment is divided by partitions.

Referring to the structure shown in Figs. 1 to 4 inclusive: At 10 is shown a sheet of cardboard or other like material which is fed to suitable dies that operate to cut out an aperture 11 in 55 the sheet. The edge 12 of the aperture defines

the shape of the merchandise-holding compartment of the box. After the aperture 11 has been cut in the sheet 10, the latter is fed to other dies which have cutting edges conforming in shape to a line defined by the edge 13 of the skeleton member or layer 14 shown in Fig. 2, these dies acting to cut a member of the shape shown at 14 from the sheet 10. A number of these members 14 are adhesively united in superimposed relationship so as to form a hollow laminated block, producing an irregularly outlined open-sided box body of substantial thickness and strength. The number of layers 14 used depends upon the depth required in the box body. In some cases, when a box of very shallow depth is desired, only one of 15 the members 14 is used. When a box body of considerable depth is required, the number of adhesively-united layer members 14 used is increased accordingly.

When a box body of the required thickness, 20 such as shown at 15 in Fig. 3, has been built up by adhesively uniting a number of the layers 14, a bottom is supplied to the box body by adhesively applying an imperforate sheet 16 to one face of the laminated box body. The sheet 16 conforms in outline to the member 14 and is produced by the dies which cut along the line 13.

The next step in the method of making the box 25 consists in forming a cover. In the structure shown in Fig. 3, which is a hinged box, the cover 17 is constructed similarly to the body of the box. That is to say, it is composed of a number of adhesively united layers 14 covered at one side by an imperforate sheet 18 conforming in shape to that forming the bottom 16 on the box body. 30 The body of the box and its cover 17 are hinged together by a sheet 19 which conforms in outline to two opposed blank members 14 and is integrally connected on the line 20 which constitutes a fold line and forms a hinge for the body of the box 35 and its cover. The edges of the box and its cover may be smoothed, colored or decorated in any suitable manner.

In Figs. 5 and 6 is shown a box provided with 40 an aperture 21 open at one end to permit the entry of a sliding tray or drawer 22 within the aperture. The box shown is similar to that of Figs. 3 and 4 as far as its method of manufacture is concerned. Its several contiguous, adhesively united layers or laminae 23 differ from the layers 45 shown at 14 only in the shape of the aperture 21 which is open at one end. The two side faces of the block of adhesively united layers 23 are covered by closure sheets 24, conforming to those shown at 16 and 18 in Fig. 3. The box so formed 50

is completely closed except for the open end of the recess 21 in which the tray is removably held.

In Figs. 7 and 8 a box body is shown formed of a number of layers 25 which are stamped out and adhesively united in the manner heretofore explained, to build up a box of required depth. The aperture 26 in this box is irregularly shaped to accommodate a bottle 40 or other irregularly shaped object. A bottom 27 is adhesively applied to the box body, and a cover 28, constructed similarly to the box body, is provided. The cover may be hinged to the body of the box in the manner described with respect to the structure shown in Fig. 3 or it may be removably secured to the box body in any other desired manner.

In the structure of Fig. 9 a box body is shown composed of a number of layers 30 adhesively united in the manner herein explained to form a box of required depth. The box body is provided with a number of spaced apertures 31, 32 and 33, having partitions 34 located between them to divide the box body into several compartments. The cover 35 for the box is constructed similarly to the body and is shown secured to the body by a hinge sheet 36 having the fold line 37 on which the cover is pivoted with respect to the box body.

The structures shown in the several views of the drawings are only a few of the many forms in which novel boxes of sturdy construction can be made from sheet material, according to the improved method. It is obvious that boxes of many other novel forms and shapes can be made according to this invention without departing from the spirit thereof.

The novel method of making boxes herein described but not claimed, is claimed in my copending application, Serial No. 736,297, filed July 21, 40 1934.

What I claim is:

1. A box having a body composed of a plurality of apertured layers of cardboard adhesively united face to face with their outlines and apertures in alignment to form a hollow laminated box body, and a closure sheet conforming in outline to the united layers secured on one end of the united layers to close one end of the aligned apertures extending therethrough.

50 2. A box having a body composed of a plurality of layers of cardboard adhesively united face to face with their outlines and apertures in alignment to form a hollow laminated box body, a

closure sheet conforming in outline to the united layers, secured on one end of the united layers and closing one end of the apertures extending therethrough, a cover member for the box, and a single apertured sheet extending over the open face of the box body and over one face of the cover member and foldable on a line between the box body and cover to hinge the cover to the box.

5 3. A box having a body composed of a plurality of cut-out cardboard sheets adhesively united face to face to form a hollow laminated box body, each of said sheets having an aperture open at one end, the various apertures being in registration when the sheets are adhesively united, closure sheets extending over the faces of the body, and a tray located in the apertures and removable through the open end thereof.

4. A box having a body and cover, respectively composed of a plurality of layers of material adhesively united face to face, said layers having 20 registering apertures therein with the apertures of the body and cover registering when assembled, a sheet adhesively secured to the outer faces of the body and cover members to close the outer ends of the respective apertures, and a single 26 sheet adhesively secured to adjacent faces of the body and cover and having apertures therein registering with the body and cover apertures and foldable on a line at corresponding edges of the body and cover to form a hinge connection there- 30 between.

5. A box having a body composed of a plurality of layers of material adhesively united face to face and each having a cut-out therein opening at one end of the layer with the cut-outs of the respective sheets registering, an imperforate closure sheet united to each face of the body and mating with the marginal edges thereof providing an end opening compartment and a slide drawer in the compartment.

40 6. A box having a body and a cover, respectively composed of a plurality of layers of material adhesively united face to face, said layers having 45 registering apertures therein with the apertures of the body and cover registering when assembled, a sheet adhesively secured to the outer faces of the body and cover members to close the outer ends of the respective apertures, and said apertures being of a configuration comparable with an article in the body whereby an article supported in the body may extend into the cover aperture for non-vibratory support therein.

FRED WINDFUHR.
